UNITED STATES PATENT OFFICE.

JACOB VEITH, OF KANSAS CITY, KANSAS.

TYPE-WRITING MACHINE.

SPECIFICATION forming part of Letters Patent No. 634,653, dated October 10, 1899.

Application filed April 18, 1898. Serial No. 678,033. (No model.)

To all whom it may concern:

Be it known that I, JACOB VEITH, a citizen of the United States, residing at Kansas City, in the county of Wyandotte and State of 5 Kansas, have invented a new and useful Type-Writing Machine, of which the following is a specification.

My invention relates to type-writing machines, and has for its object to provide a simple, compact, and efficient construction and arrangement of parts, designed particularly for letter and analogous writing, and having its parts so assembled and guided as to insure accurate alinement and the selection of the 15 desired characters with the minimum loss of time and effort on the part of the operator.

Further objects and advantages of this invention will appear in the following description, and the novel features thereof will be particularly pointed out in the appended claims.

In the drawings, Figure 1 is a perspective view of a type-writing machine constructed in accordance with my invention. Fig. 2 is a sectional view parallel with the line-spacing racks in the plane of the carriage-feeding slide. Fig. 3 is a sectional view taken parallel with the carriage-guide in a plane indicated by the line 3 3 of Fig. 2. Fig. 4 is a partial plan view showing a portion of the 25 printing-carriage in horizontal section. Fig. 5 is a detail view in perspective of the carriage-slide and the feed-pawl guide. Fig. 6 is a similar view of the feed-pawl slide, showing in dotted lines the connected extremity 30 of the actuating-spring. Fig. 7 is a detail view in perspective of the blotting-pad holder. Fig. 8 is a similar view of a portion of the carriage to show the lock seat or notch.

Similar numerals of reference indicate corresponding parts in all the figures of the drawings.

Mounted upon a base 1 is a swinging frame 2 of looped construction, with the in-turned extremities of its side arms hingedly mounted 45 upon the rear edge of the base beneath a paper-clamp 3, said paper-clamp extending parallel with the lines of writing and having a bearing front edge to rest upon the surface of a sheet of paper supported by the 50 base. This clamp is designed to hold the paper during the operation of the machine and extends outwardly over the contiguous por-

tions of the side arms of the swinging frame, whereby as the latter is elevated at its front end to introduce a sheet of paper the contact 55 of its side arms with the projecting portions or extensions of the paper-clamp will raise the latter against the tension of the yielding means employed for holding the clamp in place, the yielding means illustrated in the drawings 60 consisting of springs 4, coiled upon guide-pins 5, the latter preferably consisting of screws threaded into the rear edge of the base, whereby the tension of the springs may be varied. These guide-pins extend through vertically- 65 elongated slots 6 in the paper-clamp to allow a limited tilting movement of the clamp when actuated by the side arms of the swinging frame.

The side arms of the swinging frame are 70 disposed transversely or perpendicularly to the lines of writing, and terminally mounted thereon is a carriage-guide 7, preferably constructed of sheet metal and having its opposite edges folded inwardly to form, respectively, a single lap 8, terminating in a feed-rack 9 and a double lap 10, of which the inner edge is turned under and outwardly to engage the lapped front edge of a carriage-slide 11. The inwardly-folded front edge of 75 the carriage-slide 11 constitutes a guide-rib 12, of which the front edge fits in the guide-groove formed by the lapped front edge of the carriage-guide, and the rear edge of said carriage-guide is preferably folded upon it- 80 self, as shown at 13, to fit in the single-lapped rear edge of the carriage-guide, and thus insure the accurate guiding of the slide to pre- 85 serve the alinement of the printing characters. The double-lapped front edge of the 90 carriage-guide also constitutes a friction-spring, which resists the feeding movement of the carriage-slide sufficiently to prevent the excessive advance thereof without unne- 95 cessarily impeding the same.

The carriage-slide is provided with a flanged carrier 14, of which the center is depressed, and secured to the slide between the rack 9 and the double-lapped front edge of the carriage-guide and secured to the carrier is a 100 flanged feed-pawl guide 15, in which is mounted a feed-pawl slide 16. This feed-pawl slide is flanged at its lower edge to fit in the interior of the guide 15, and carries a

feed-pawl 17, consisting of a tongue which is bifurcated at its free extremity to engage the teeth of the feed-rack 9, said feed-pawl slide having a rearwardly-extending tongue 18 operating in an extension of the feed-pawl guide 15 and having a retracting-spring 19 connected therewith. The feed-pawl slide 16 also includes an upturned ear 16^a, having a bevel or cam faced rear edge 20, which projects in rear of a guide-ear 21, rising from the carrier 14.

The printing-carriage consists of an elongated box 22, also struck from sheet metal, with one side edge flanged, as shown at 23, and the other edge rolled to form a double lap 24 for engagement with the correspondingly-lapped edge of the index-slide 25, the flange 23 of the carriage-box being engaged by the undeturned contiguous edge of the index-slide 25. This index-slide covers the box of the carriage and constitutes a cap or cover therefor, and parallel with the index, which consists of printing characters, such as letters and numerals, and formed in the underlapped edge of the cap is a series of holding-seats 26, arranged, respectively, opposite the printing characters and adapted for respective registration with a lock notch or seat 27, formed in the flange 23. Said index-slide is provided with a knob or handle 28, whereby the slide may be moved transversely to the lines of writing to arrange either of the seats 26 in registration with the lock notch or seat 27.

The index-slide is provided with a depending wing 29, arranged within the carriage-box and carrying at its lower edge a forwardly-extending approximately horizontal flexible web 30, upon which are arranged type-heads 31, of rubber or other suitable material, said type-heads facing downwardly for depression through an impression-opening 32 in the floor of the carriage, said impression-opening being arranged in the vertical plane of the lock-seat 27. Also arranged within the carriage is a plurality of inking-pads 33, constructed of suitable absorbent material and arranged in pad-holders 34, which bear against one side wall of the carriage and are connected by a spring-rod 35, which bears against the opposite side wall of the carriage. This pad-holder is removable from the carriage after moving the index-slide to discover the same in order that the pads may be replaced or supplied with ink. Also arranged in the plane of the impression-opening is an impression-plunger 36, supported by a spring-arm 37, which is disposed in the plane of and contiguous to the lock notch or seat 27 and extends over the slide 25, whereby the depression of the plunger to bring it in contact with the back or upper surface of the type-head-supporting web will also bring said arm into engagement with the lock-seat and the registering holding-seat 26 of the slide. The spring-arm may, as illustrated in the drawings, be attached to the carriage at the oppo-

site side from that in which the lock-seat is formed.

Arranged in operative relation with an offset portion or shoulder 38 of the plunger-supporting arm is an impression-lever 39, which is pivoted to the side wall of the carriage and operates at an intermediate point between said side wall and the parallel contiguous edge of the guide-ear 21, the free end of said lever being provided with a finger-plate 40. This impression-lever, however, is also arranged in operative relation with the bevel or cam faced edge of the feed-pawl slide 16, whereby at each depression of the impression-lever the first portion of its movement causes the advance of the slide 16, and hence the feeding movement of the impression-carriage, through a distance equal to a letter-space. The cam-face 20 of the slide-ear 16^a, however, is of less length than the amplitude of movement of the impression-lever, whereby after the impression-carriage has been advanced through a letter-space, as above indicated, said lever traverses a vertical portion of the edge of the ear 16^a. This continued motion of the impression-lever is communicated to the supporting-arm of the impression-plunger, which, being brought into contact with the back of the type-head-supporting web, depresses that type-head which is located at the printing-point to bring its printing-face into contact with the sheet or printing-surface supported by the base.

From the above description it will be seen that in operation the index-slide may be moved by one hand of the operator to successively arrange the holding-seats 26 in the plane of the lock seat or notch 27, and when so positioned the depression of the front end of the lever 39 by means of the other hand will cause, first, the feeding movement of the carriage through one letter-space, and subsequently the impression of a printing character upon the surface of the sheet, the plunger, impression-lever, and feed-pawl being immediately returned to their normal positions, when the impression-lever is relieved of pressure by the springs provided for that purpose. It will be understood that the supporting-arm of the plunger is of yielding construction to return the impression-lever, while the feed-pawl is provided with an actuating-spring, as hereinbefore explained.

The machine as described is preferably constructed mainly of sheet metal, all of the parts being of such material except the swinging frame 2, the impression-lever, and the plunger-supporting arm and actuating-springs.

Secured to the base at the side edges and perpendicular to the lines of writing are line-spacing racks 41, provided with spaced sockets 42 to receive holding pins or spurs 43, which depend from the carriage-guide 7, and in order that the carriage-guide may be elevated to disengage said pins or studs from one pair of sockets 42 and advanced for engage-

ment with the next pair without affecting the engagement of the paper-clamp with the sheet arranged on the base the terminal projecting portions or extensions of said clamp are preferably spaced slightly above the arms of the swinging frame, as shown. In this way the swinging frame is capable of a limited swinging movement before its arms come in contact with the projections or extensions of the clamp, whereas a continuation of the swinging movement of said frame will result in elevating the front edge of the clamp sufficiently to remove a sheet or insert one which is to receive the impressions of the printing characters.

In the construction illustrated the carriage-guide is mounted upon the side arms of the swinging frame by means of a base-spanning strap 44, folded upon itself at the ends of the guide to form eyes 45, fitted upon said side arms of the frame.

It will be obvious that a machine constructed as shown and described may be manufactured at a comparatively small cost and may be manipulated with sufficient facility to adapt it particularly for letter-writing and analogous uses, and in order that the selection of the proper characters may be accomplished without the necessity of learning the arrangement of an arbitrary keyboard I have deemed it preferable to locate the index characters consecutively or alphabetically.

A further advantage of the construction described resides in the fact that a pad or block of paper may be arranged upon the base between the line-spacing racks, each sheet being detached as it is used. Envelops and small sheets to receive the impressions of the printing characters may be held in place by inserting the edges thereof under the line-spacing racks, of which the portions which rest upon the surface of the base are secured only adjacent to their extremities. In other words, the intermediate portions of the line-spacing racks are spaced sufficiently from the plane of the surface of the base to allow the insertion of the edge of a sheet or an envelop.

In practice various changes in the form, proportion, and the minor details of construction may be resorted to without departing from the spirit or sacrificing any of the advantages of this invention.

Having described my invention, what I claim is—

1. In a type-writing machine, the combination with a base, of a swinging frame mounted upon the base for movement toward and from the plane thereof, a printing-carriage and feeding device carried by said frame, and a paper-holding clamp mounted upon the base for securing a sheet in contact with the surface thereof, and provided with means for engagement by the frame, whereby the clamp is moved when the frame is raised, substantially as specified.

2. In a type-writing machine, the combination with a base, of a swinging frame mounted

upon the base for movement toward and from the plane thereof, a printing-carriage and feeding devices carried by said frame, and a paper-holding clamp yieldingly held in its operative position with relation to the base and displaceable by said frame, when the latter is moved from its operative position, to release a sheet on the base, substantially as specified.

3. In a type-writing machine, the combination with a base, of a swinging frame mounted upon the base for movement toward and from the plane thereof, a printing-carriage and feeding devices carried by said frame, and a paper-holding clamp yieldingly mounted upon the base and having extensions arranged in the paths of the arms of said swinging frame, substantially as specified.

4. In a type-writing machine, the combination with a base, of a swinging frame mounted upon the base for movement toward and from the plane thereof, a printing-carriage and feeding devices carried by said frame, and a paper-holding clamp yieldingly mounted upon the base and having extensions arranged in the paths of the arms of said swinging frame for elevation thereby, and spaced from said arms to allow a limited independent movement of the frame, substantially as specified.

5. In a type-writing machine, the combination with a base, of a swinging frame mounted upon the base for movement toward and from the plane thereof, a printing-carriage and feeding devices carried by said frame, and a paper-holding clamp mounted upon the base with its extremities arranged in the paths of the arms of said swinging frame, actuating-springs for maintaining said clamp in its operative position, and means for varying the tension of the actuating-springs, substantially as specified.

6. In a type-writing machine, the combination with a base, of a swinging frame mounted upon the base for movement toward and from the plane thereof, a printing-carriage and feeding devices carried by said frame, and a paper-holding clamp arranged upon the base with terminal extensions arranged in the paths of the arms of the swinging frame, said clamp having transversely-elongated openings, guide-pins extending through said openings and consisting of screws threaded into the base, and springs coiled upon the guide-pins and bearing upon the clamp to maintain it yieldingly in its operative position, substantially as specified.

7. In a type-writing machine, the combination with a base, of a swinging frame mounted thereon and carrying a printing-carriage and feeding devices including a carriage-guide arranged parallel with the lines of writing, said carriage-guide being movable upon the frame in a direction transverse to the lines of writing, line-spacing racks on the base, and pins or studs carried by said carriage-guide for engagement with the line-spacing racks to secure the carriage-guide at the desired line adjustment, substantially as specified.

8. In a type-writing machine, the combination with a base, of a swinging frame, a printing-carriage and feeding devices including a carriage-guide mounted upon the side arms 5 of the swinging frame for movement parallel therewith and transverse to the lines of writing, line-spacing racks fixed to the base transversely to the lines of writing and provided with spaced sockets, and pendent pins or studs 10 on said carriage-guide for engagement with opposite sockets of the line-spacing racks, substantially as specified.

9. In a type-writing machine, the combination with a base, of a looped swinging frame 15 mounted upon the base and having parallel side arms arranged transversely to the lines of writing, a carriage-guide having terminal eyes fitted to slide upon the side arms of said swinging frame, a printing-carriage mounted 20 upon said carriage-guide for movement parallel with the lines of writing, carriage-feed mechanism operatively connected with the printing mechanism, and including a pawl for engagement with a rack on said carriage- 25 guide, stationary line-spacing racks on the base, and studs carried by the said carriage-guide for engagement with the line-spacing racks, substantially as specified.

10. In a type-writing machine, the combination with a base, of a carriage-guide mounted 30 for movement transversely to the lines of writing, and having its front and rear edges provided respectively with a double-lapped guide and an inturned rack, a carriage-slide 35 fitted in the carriage-guide for movement parallel with the lines of writing, a spring-actuated feed-pawl slide carrying a pawl for engagement with said rack, a carriage supported by the carriage-slide and having printing 40 mechanism including an impression-lever, and a cam-faced ear on the feed-pawl slide arranged in the path of said lever, substantially as specified.

11. In a type-writing machine, the combination with a base, of a carriage-guide arranged 45 parallel with the lines of writing, a carriage-slide fitted in said guide and having an interlocking connection therewith, said carriage-guide being provided with a rack, a printing-carriage mounted upon said carriage-slide and having printing mechanism including an impression-lever, a guide-ear on the carriage-slide having its guiding edge spaced from the adjacent wall of the printing-carriage, to guide the movements of the impression-lever, a feed-pawl slide mounted 55 in a guide on the carriage-slide and provided with a return-spring, and a cam-faced ear on said feed-pawl slide arranged in the path of the impression-lever, substantially as specified.

12. In a type-writing machine, the combination with a base, of a carriage-guide arranged 60 parallel with the lines of writing, a carriage-slide fitted frictionally in said carriage-guide, a printing-carriage supported by the carriage-slide and having printing charac-

ters including an impression-lever, a spring-actuated feed-pawl slide including a feed-pawl arranged in operative relation with a feed-rack on said carriage-guide, and operating connections between said impression-lever and the feed-pawl slide, including a cam-face arranged in the path of the impression-lever and of a length less than the amplitude 70 of movement of said lever, whereby the movement of the feed-pawl, to advance the carriage, occurs during the first portion of the movement of the impression-lever, substantially as specified.

13. In a type-writing machine, the combination with a base, of a sheet-metal carriage-guide arranged parallel with the lines of writing and having respectively double and single lapped front and rear edges, the single-lapped 80 rear edge being constructed to form a feed-rack, a carriage-slide fitted in said guide and having, respectively, double and single lapped front and rear edges in frictional contact with the surfaces of the guide and held thereby 85 against excessive movement, a printing-carriage including printing mechanism, and carriage-slide-feeding mechanism operatively connected with the printing mechanism, substantially as specified.

14. In a type-writing machine, the combination of a carriage-guide arranged parallel with the lines of writing, line-spacing mechanism for adjusting said guide, a printing-carriage mounted for movement parallel with 100 the carriage-guide, and including an index-slide mounted for movement transversely to the lines of writing, and carrying printing-type, impression devices for successively actuating the printing-type, and including an 105 impression-lever, and a plunger, in the path of which said printing-type may be successively arranged, said plunger being actuated by the impression-lever and carriage-feeding mechanism operatively connected with the 110 impression-lever, substantially as specified.

15. In a type-writing machine, the combination of a carriage-guide arranged parallel with the lines of writing, line-spacing mechanism for adjusting said guide, a printing-carriage mounted upon said guide and having 115 a body portion, and an index-slide mounted for movement upon the body portion in a direction transverse to the lines of writing, a flexible type-head carrying a web supported 120 by said index-plate, a reciprocable printing-plunger arranged in the plane of the printing-point, to depress the registering type-head, an impression-lever for actuating said plunger, and carriage-feeding mechanism operatively connected with the impression-lever, 125 substantially as specified.

16. In a type-writing machine, the combination of a carriage-guide arranged parallel with the lines of writing, line-spacing mechanism for adjusting said guide, a printing-carriage mounted upon said carriage-guide and having a body portion consisting of an 130 elongated box, and an index-slide mounted

- upon said box and carrying a flexible web provided with type-heads, said web being housed within the box, a reciprocable plunger mounted upon the box in the plane of the printing-point, to depress the alined type-head, an impression-lever for actuating said plunger, and carriage-feeding mechanism operatively connected with the impression-lever, substantially as specified.
17. In a type-writing machine, the combination of a carriage-guide arranged parallel with the lines of writing, line-spacing mechanism for adjusting said guide, a printing-carriage mounted upon said guide and having an elongated body portion, and an index-slide mounted upon said body portion for movement transversely to the lines of writing, a yieldingly-supported plunger arranged in the plane of the printing-point, a flexible type-head-carrying web supported by said index-slide, inking-pads arranged in the paths of the type-heads, and plunger-operating and carriage-feeding devices, substantially as specified.
18. In a type-writing machine, the combination of a carriage-guide arranged parallel with the lines of writing, line-spacing mechanism for adjusting said guide, a printing-carriage having a hollow body portion and an index-slide mounted upon said body portion for movement transversely to the lines of writing, a yieldingly-supported plunger arranged in the plane of the printing-point, a type-head-supporting web carried by the index-slide, and adapted to be arranged with either of its type-heads in the path of the plunger, inking devices including spaced inking-pads removably fitted in said body portion of the carriage upon opposite sides of the plane of the plunger and in the path of the type-heads, and plunger-operating and carriage-feeding devices, substantially as specified.
19. In a type-writing machine, the combination of a carriage-guide arranged parallel with the lines of writing, line-spacing mechanism for adjusting said guide, a carriage having a hollow parallel-walled body portion and an index-slide mounted thereon for movement transversely to the lines of writing, a yieldingly-supported plunger arranged in the plane of the printing-point, a type-head-supporting web carried by the index-slide, said type-heads being adapted for successive arrangement in the path of the plunger, spaced inking-pads, an ink-pad holder having terminal seats bearing against one wall of the body portion of the carriage upon opposite sides of the plane of the plunger, and a connecting-spring bearing against the opposite wall thereof, and plunger-operating and carriage-feeding devices, substantially as specified.
20. In a type-writing machine, the combination of a carriage-guide arranged parallel with the lines of writing, line-spacing mechanism for adjusting said guide, a carriage having a body portion mounted upon said guide and an index-slide mounted upon the body portion for movement transversely to the lines of writing, said body portion being provided with a lock-seat, and the slide with a plurality of holding-seats for successive registration with the lock-seat, a type-head-supporting web carried by the index-slide, a plunger arranged in the plane of the printing-point and having a supporting-arm for engagement with the lock-seat and the registering holding-seat of the index-plate, and plunger-operating and carriage-feeding devices, substantially as specified.
21. In a type-writing machine, the combination of a carriage-guide arranged parallel with the lines of writing, line-spacing mechanism for adjusting said guide, a printing-carriage having a sheet-metal body portion mounted upon said guide and provided at one edge with a flange having a lock-seat, and at the other edge with a roll, and an index-slide rolled and lapped at its opposite edges to respectively engage said roll and flange of the body portion, and provided in its lapped edge with a series of holding-seats for successive registration with said lock-seat, a type-head-supporting web carried by the index-slide, a printing-plunger arranged in the plane of the printing-point and having a spring-supporting arm for engagement with said lock-seat and the registering holding-seat when the plunger is depressed, and plunger-operating and carriage-feeding devices, substantially as specified.
22. In a type-writing machine, the combination of a carriage-guide arranged parallel with the lines of writing, line-spacing mechanism for adjusting said guide, a printing-carriage having a sheet-metal body portion mounted upon said guide and provided at one edge with a flange having a lock-seat, and at the other edge with a roll, and an index-slide rolled and lapped at its opposite edges to respectively engage said roll and flange of the body portion, and provided in its lapped edge with a series of holding-seats for successive registration with said lock-seat, a type-head-supporting web carried by the index-slide, a printing plunger arranged in the plane of the printing-point and having a spring-supporting arm for engagement with said lock-seat and the registering holding-seat when the plunger is depressed, and plunger-operating and carriage-feeding devices, including a pivotal impression-lever mounted upon said body portion of the carriage in operative relation with an offset or shoulder of said plunger-supporting arm, substantially as specified.
- In testimony that I claim the foregoing as my own I have hereto affixed my signature in the presence of two witnesses.
